UNITED STATES PATENT OFFICE.

JOHN C. BLAIR, OF WILMINGTON, DELAWARE.

ORE-RAKE.

SPECIFICATION forming part of Letters Patent No. 487,511, dated December 6, 1892.

Application filed May 14, 1892. Serial No. 433,395. (No model.)

To all whom it may concern:

Be it known that I, JOHN C. BLAIR, a citizen of the United States, residing at Wilmington, in the county of New Castle and State of Delaware, have invented certain new and useful Improvements in Ore-Rakes; and I do hereby declare the following to be a full, clear, and exact description of the invention, such as will enable others skilled in the art to which it applies to make and use the same.

This invention is an improvement in rakes and rake-heads such as are used in furnaces for roasting ores, in which series of beds arranged one above the other communicate by means of alternate passages or openings at the end of the beds. Rakes of this kind are designed for the purpose not only of stirring the pulverized ore upon the beds, so that it will burn easily and thoroughly thereon, but it is essential that the ore shall be propelled along the bed by some positive means in one direction.

Heretofore rakes have been made which consisted merely of teeth having a triangular section, the front of the teeth pointing in the direction in which the rake is designed to plow through the ore and the rear or flat sides of the teeth being toward that side of the furnace-bed toward which it is desired to push the ore. It has been found by a long course of experiments that this does not so effectually and positively move the ore in one direction as is necessary in burning some ores, such as iron pyrites, and therefore it has been the object of this invention to provide a more sure and certain means for pushing the ore positively in either direction.

With this object in view the invention resides in the various novel details of construction and in the combination of parts herein-after fully described, and particularly pointed out in the claims.

In the drawings in which I have illustrated my invention, and in which like letters of reference indicate corresponding parts, Figure 1 is a longitudinal vertical section through a furnace in which my improved rake is used, showing the rakes in their proper position relative to the furnace and to each other. Fig. 2 is a perspective view showing in detail the rake and scraper as seen from the under side. Fig. 3 is a cross-section of the rake, showing the

position of the scraper during a forward movement. Fig. 4 is a detail cross-section showing a guide c' resting on rail c^2 .

In the drawings the letter A designates the furnace proper, and the letters a indicate the beds arranged in series one above the other therein. Each one of the beds is provided with an opening a' , and these openings are so arranged as to be in the alternate ends of each adjoining bed. A feeding-hopper a^2 is provided near the top of the furnace, and a receptacle a^3 is provided at the bottom thereof.

The raking mechanism proper consists of the usual carriage B, the rods B' extending from the carriage through openings in the furnace to the rake-heads and the power or driving mechanism B^2 .

The rake-head, which is designated by the letter C, is constructed as follows: To pieces of angle-iron C' are secured the teeth c , which in cross-section are triangular, or the body of the rake and the teeth may be cast integral.

On either side of the head I provide depending sliding surfaces c' , which are designed to move upon tracks or rails c^2 , which are provided within the furnace for the rake-head to move upon. The sliding surfaces c' have guards c^3 to retain them upon the rails. Across the top of the rake-head I secure two bars C^2 ,

and these bars, projecting beyond one end of the rake-head, are provided with depending brackets c^4 , in which is pivotally hung the scraper or shovel D. These brackets c^4 are provided with loose bearings c^5 , wherein the scraper D may turn upon its pivotal points and with lugs or stops c^6 at the bottom and c^7 at the top to prevent the shovel D from turning more than a quadrant in any one move-

ment. The shovel D consists only of a piece of metal having a flat outer side, a flat inner side rounded or curved near the bottom, trunnions at the top, (marked d), and cut-away portions below these trunnions, leaving arms or projections d' , which impinge against the stops c^6 c^7 .

The shovel D is always hung upon that side of the rake, whether it be the inner or the outer side in reference to the rods B' , toward which it is desired to push the ore. In the drawings it will be seen that the shovel which works upon the upper bed is hung upon the inner side of the rake-head, having regard to the rods B' , and the shovel upon the

rake-head working upon the second bed is hung upon the outer side of the rake-head, and so on, alternately from bed to bed.

From the foregoing description it will be obvious that in moving the rakes backward and forward through the pulverized ore the combined rake and shovel will, in what may be called its "forward movement," curry or comb the ore, thus gently turning the particles and presenting them for combustion, while by a reverse motion the shovel resting against the stops c^6 will push the ore toward the opening a' . In the forward motion the shovel is raised by the ore itself to any height less than or equal to that allowed by the stop c^7 . It will be observed that the shovel hangs a little higher than the bottom of the rake-teeth, thus leaving a space between its lower edge and the bed over which it works. Therefore it will be apparent that it will take several movements of the rake-head backward and forward completely to change the ore upon any one bed, as only a small portion relatively is moved at one time.

It is of course to be understood that while I have described my rake-head as moving upon sliding surfaces over tracks or ways provided upon the bed of the furnace I may,

without departing from the spirit of my invention, employ wheels or rollers in place of 30 the sliding surfaces.

Having thus fully described my invention, what I claim as new, and desire to secure by Letters Patent of the United States, is—

1. The combination, in a reciprocating ore-stirrer, of a rake-head carrying triangular teeth having their points all in one direction and their flat rear surfaces in parallel planes, with a shovel or scraper pivoted to the rake-head in a plane parallel to the flat surfaces 40 of the rake-teeth and on the side of the teeth nearest to said flat surfaces, substantially as and for the purpose set forth.

2. The combination, in a reciprocating ore-stirrer, of a rake-head having projecting from one side of it the bars C^2 , having depending brackets c^4 , with the shovel or scraper D pivoted in these brackets and limited in its motion by means of lugs thereon, all substantially as and for the purpose set forth.

In testimony whereof I affix my signature in presence of two witnesses.

JOHN C. BLAIR.
